UNITED STATES PATENT OFFICE.

JOHN H. J. RONNER, OF NEW YORK, N. Y.

CLOTHES-HANGER.

SPECIFICATION forming part of Letters Patent No. 536,483, dated March 26, 1895.

Application filed October 6, 1894. Serial No. 525,119. (No model.)

To all whom it may concern:

Be it known that I, JOHN H. J. RONNER, of New York city, in the county and State of New York, have invented a new and Improved 5 Clothes-Hanger, of which the following is a full, clear, and exact description.

My invention relates to improvements in clothes hangers; and the object of my invention is to produce an extremely simple and 10 cheap device, which is adapted to hold an entire suit of men's clothes and may be also made to support other garments, also to produce a device which is constructed in such a way that the clothes may be easily applied to 15 or removed from it, and to arrange the hanger so that the clothes which it supports will be held in such a way as to prevent them from becoming creased or out of shape.

To these ends my invention consists of cer- 20 tain features of construction and combina- tions of parts, which will be hereinafter de- scribed and claimed.

Reference is to be had to the accompanying 25 drawings, forming a part of this specification, in which similar figures of reference indicate corresponding parts in all the views.

Figure 1 is a perspective view of the clothes hanger embodying my invention. Fig. 2 is a perspective view of the clothes hanger with 30 the fastening nut arranged at the top instead of at the bottom. Fig. 3 is a perspective view of another modification of the clothes hanger. Fig. 4 is a perspective view of the form of hanger shown in Fig. 1, but with sleeve sup- 35 ports attached; and Fig. 5 is a cross section of the form of hanger shown in Fig. 1.

The hanger is provided with oppositely ar- 40 ranged clamping jaws 10 and 11 which are placed one above the other, the jaw 10 being oval in longitudinal section and also in cross section, so that a coat or other garment, may lie smoothly on it, and the upper edges of the lower jaw 11 are beveled, as shown at 12, to prevent the jaw from creasing the trousers or 45 other garment which may be held between it and the upper jaw. The hanger is provided with a hook 13, which has a screw shank 14 long enough to extend through the central portion of both jaws 10 and 11, and on the 50 shank of the hook is a burr 15, or similar abut- ment, which rests on the top of the upper jaw 10 and on the lower end of the screw shank is a thumb nut 16 which is adapted to abut

with the lower jaw 11 and, by turning up this nut, the jaws may be clamped firmly together. 55

In hanging trousers the trousers are placed bottom side up and the lower ends clamped between the upper and lower jaws 11 and a waistcoat or other garment may be fastened in a similar way. A coat is placed over the 60 upper jaw 10, the ends of the jaw projecting into the upper portions of the coat sleeves, and it will be seen that an entire suit may be thus secured to the hanger and the latter may be suspended by the hook 13. 65

As shown in Fig. 2, the hanger is provided with a suspending hook 13, like that already described, but the hook has a head 17 at the lower end, and a thumb nut 16 is placed on the shank 14 of the hook above the upper jaw 70 10 and the jaws are clamped together by turning down the nut.

In Fig. 3 the lower jaw 11 is provided with a fixed nut 18 through which the shank 14 of the hook 13 extends, and the two jaws may 75 be clamped together or separated by turning the hook and its shank.

In Fig. 4 I have shown the hanger provided with sleeve supports, which may be attached to either form of the hanger, and each support 80 consists of a transversely placed wire loop 19, the ends 20 of which are sprung into holes in the sides of the upper jaw 10, as the drawings clearly show. These loops are adapted to project into the sleeves of a garment and sup- 85 port the shoulders, so that for this reason the sleeve supports are especially adapted for use when a lady's garment with big sleeves is to be hung on the hanger.

Having thus described my invention, I 90 claim as new and desire to secure by Letters Patent—

A clothes hanger comprising two separable jaws having oppositely arranged clamping faces, a suspending hook having a screw 95 threaded shank extending through both jaws, a burr on the upper end of the shank adapted to bear on the upper face of the upper member and a nut screwing on the lower end of the shank, below the lower jaw substantially 100 as set forth.

JOHN H. J. RONNER.
